WORK SUPPORTING DEVICE

Lester B. Hooper, Beverly, Mass., assignor to
United Shoe Machinery Corporation, Paterson,
N. J., a corporation of New Jersey

Application May 14, 1934, Serial No. 725,442

2 Claims. (Cl. 164—79)

This invention relates to work holding devices and is herein illustrated as embodied in a machine for producing blanks from sheet material by means of dies.

5 In the production of blanks such as shoe part blanks from sheet material use is commonly made of a machine having a work support in a form of a cutting block and an arm or beam arranged to reciprocate relatively to the block 10 for forcing a freely movable die through the material. In some classes of work, such as in the cutting of linings for shoes, the blanks are cut from rolls of fabric one or more layers of which are drawn up over the edge of the block and held in position upon the block by some form of 15 clamp commonly called a cloth clamp. Devices of this kind are utilized in order to maintain one end of the material upon the cutting block against the weight of the bight of the material and 20 against displacement by the operator in locating a die upon the work.

It is an object of the invention to provide a work holding device of improved construction which will be particularly effective to hold the 25 material upon a cutting block and at the same time will be simple in its operation and cheap to manufacture. To this end and as illustrated herein, the invention provides a work holding device comprising an apron having a curved 30 work engaging surface extending along one side of the work support of a machine for operating on sheet material together with members pivotally mounted adjacent to the apron and arranged for angular movement into engagement with the 35 apron for clamping and holding material extending over the apron.

Other features and objects of the invention will be apparent from the following detailed description when taken in connection with the accompanying drawing and will be pointed out in the 40 claims.

In the drawing,

Fig. 1 is a side view of a portion of a clicking machine equipped with a work holding device 45 constructed in accordance with the invention; and

Fig. 2 is a plan view showing the work holding device in position upon the cutting block of the machine.

50 The illustrated machine is a clicking machine comprising a frame 10, a bed 12 supporting a wooden cutting block 14 which is secured to the bed by clamping bolts 16. At the forward portion of the bed there is a bracket 18 secured to the bed by bolts 20 and having upturned arms 22

which support a shaft 24. Loosely mounted upon the shaft 24 are a plurality of fingers 26 spaced along the shaft by collars 28 and having their free ends rounded. The rounded ends of the fingers are normally adapted to contact with an apron 30 formed of wood or of metal and secured to the arms 22 by bolts 32. The apron 30 acts as an abutment which may be engaged by the fingers and over which sheet material may be guided as it is located upon the cutting block 14. 5 This is shown in Fig. 1 wherein the end 34 of a roll of sheet material 35 which is carried in a trough 36 at the base of the machine has been drawn upwardly over the apron 30 and located upon the upper surface of the block 14. It is 10 to be noted that the apron 30 is provided with a concave surface 38, the curvature of which is eccentric to the axis of the shaft 24, the lower portion of the apron 30 being nearer the shaft 24 than the upper portion. The lengths of the 15 fingers 26 are such that as the fingers are rotated about the axis of the shaft 24 there will be clearance between the fingers and the surface 38 at the top of the apron but as the ends of the fingers are moved downwardly they will engage some 20 portion of the surface 38, or the surface of material extending over the apron. This construction provides for automatic operation of the 25 fingers regardless of the thickness of the layer or layers of the sheet material drawn over the 30 apron, the fingers accommodating themselves to the varying thickness of the material. The 35 weight of the fingers is such that sufficient pressure will be brought to bear upon material positioned between the fingers and the surface 38 at several points along the apron so that the material will be held in position.

The construction of the device is such that after a sheet of material is brought up onto the 40 surface of the block and then released any tendency of the depending portion of the material to pull the end downwardly will result in forcing the fingers in a clockwise direction about their supporting shaft so that the material will be 45 pinched between the ends of the fingers and the curved portion 38 of the apron, thus to prevent any further movement of the material. On the other hand, when it is desired to draw more material across the upper surface of the cutting 50 block a movement of the material in an upward direction will rotate the fingers in a counter-clockwise direction and release their pressure upon the material.

Having described my invention, what I claim as 55

new and desire to secure by Letters Patent of the United States is:

1. A work holding device comprising a work support, an apron extending along one edge of the support and having a concave surface over which sheet material may be drawn, a shaft spaced from the surface, and a plurality of fingers loosely mounted upon the shaft, the lengths of the fingers being greater than the shortest distance between the axis of the shaft and the concave surface.

2. A work holding device comprising a work

support, an apron extending along one side of the support and having a concave curved surface over which sheet material may be drawn, a shaft extending along the apron, the axis of the shaft being eccentric to the axis of the curved surface, and work engaging members loosely mounted upon the shaft and movable angularly into engagement with sheet material positioned upon the support and extending across the curved surface.

LESTER B. HOOPER.
